UNITED STATES PATENT OFFICE

2,073,529

ELECTRIC SWITCH

Robert F. Sambleson, Bridgeport, Conn., assignor
to General Electric Company, a corporation of
New York

Application November 15, 1935, Serial No. 49,928

5 Claims. (Cl. 200—153)

The present invention relates to double-pole electric switches of the type having a liquid contact circuit closer for controlling one side of a two wire circuit and mechanical contacts for controlling the other side of the two wire circuit.

The object of my invention is to provide an improved construction and arrangement in a switch of this type, and for a consideration of what I believe to be novel and my invention, attention is directed to the accompanying description and the claims appended thereto.

In the accompanying drawing, Fig. 1 is a plan view partly broken away of a switch embodying my invention; Fig. 2 is a perspective view partly in section; Fig. 3 is a diagrammatic view showing the construction and operation of the liquid contact circuit closer; and Fig. 4 is a sectional view taken on line 4—4 of Fig. 1.

Referring to the drawing, I have illustrated my invention using a liquid contact circuit closer having a pair of cup-shaped metal terminals 1 which are separated by an insulating diaphragm 2 of refractory material, such as a ceramic. The edges of the terminals are sealed by a bead 3 of glass which also seals the junctions between the diaphragm and the terminals. Within the space enclosed by the terminals is a suitable quantity of mercury 4 which forms the conducting medium between the terminals. In the manufacture of the switch, the space enclosed by the terminals is evacuated and filled with hydrogen at a pressure of one or more atmospheres which increases the current interrupting capacity of the circuit closer. As shown in Fig. 3, the diaphragm 2 is provided with an opening 5 which is submerged in the mercury when the circuit closer is in the current conducting position, as shown by the dotted lines in Fig. 3. When the circuit closer is in the current interrupting position shown in full lines in Fig. 3, the opening 5 is above the mercury, and the circuit between the terminals is therefore interrupted by the insulating diaphragm 2. Due to the construction of the circuit closer, the interruption of the circuit between the terminals takes place in the mercury as the circuit closer is turned so that the opening 5 in the diaphragm approaches the full line position. The above-described construction is illustrative of a liquid contact circuit closer which is suitable for use in a switch embodying my invention.

The circuit closer is mounted within a housing 6 having side walls 7a and 7b and a central partition 8. Between the side wall 7a and the partition 8 is a pair of contacts 9, which, as shown

in Fig. 4, are secured to bosses 10 on the housing by the spun-over portions 11 of inserts 12 molded in the bosses. Terminal screws 13 are threaded into the inserts 12 and provide a means for clamping the line conductors of one side of a two wire circuit to the contacts 9. The bottom edges of the contacts 9 rest on shoulders 14 formed respectively on the partition 8 and the side wall 7a. The portions of the contacts 9 adjacent the terminals 1 of the circuit closer are provided with circular projections 15 which fit into complementary recesses 16 in the terminals. The projections 15 and the depressions 16 provide ball and socket connections which support the circuit closer and permit it to rotate about its axis. 15 The wiping action between the terminals and the contacts tends to prevent increase of contact resistance. The contacts 9 are prevented from spreading by the side wall 7a and the partition 8 so that the liquid contact circuit closer is securely held between the contacts. 20

Between the partition 8 and the side wall 7b are spring strips 17 which are secured at one end to bosses 18 on the housing in the same manner that the contacts 9 are secured to the bosses 10. 25 Terminal screws 19 are threaded into the inserts 12 which secure the spring strips 17 to the housing and form the terminals for the other side of the two wire circuit of the switch. On the inner ends of the spring strips 17 are contacts 20 30 which are normally biased together by the resilience of the spring strips.

For operating the switch, I have provided a handle 21 having a curved flange 22 at its lower end which rests on the curved surface 23 of the partition 8 and also having a curved flange 24 on the other side of the handle which fits over the terminal of the circuit closer adjacent the partition 8. The surface 24 of the handle is provided with a projection 25 which fits into a complementary recess 26 in the terminal and prevents relative rotation between the circuit closer and the handle. The curved surface 23 provides a bearing on which the handle turns. The handle is held in place by spring strips 27 40 which engage projections 28 formed on each of the flanges 22 and 24. The portions of the spring strips 27 which engage the projections 28 are relatively flat compared to the curved flanges 22 and 24 of the handle so that it is apparent that 50 the springs tend to bias the handle to either side of the central position. At either end the spring strips 27 are bent to provide resilient stops 29 which engage the sides of projections 28 and limit the movement of the handle 21. The stops 55

29 are resilient and therefore decrease the noise resulting from the impact of the projections 28 with the stops. The spring strips 27 are riveted to a mounting strap 30 which is secured to the 5 housing by screws 31 extending through the housing from the bottom. The mounting strap is used for mounting the switch in an outlet box and, when so mounted, the right-hand end of the mounting strap should be at the top. A dust 10 cover 32 encloses the upper side of the housing.

The flange 22 of the handle is provided with a depending rod 33 of insulating material which, as shown in Figs. 2 and 3, is adapted to engage the lower spring strip 17 and separate the contacts 20 when the handle 21 is moved to the upper position.

In the assembly of the switch, the spring strips 17 are secured to the bosses 18 by the spun-over portions 11 of the inserts 12, and the terminal 20 screws 19 are threaded into the inserts. The contacts 9 are then assembled on each side of the liquid contact circuit closer so that the projections 15 fit within the depressions 16 in the terminals. Before assembly, the ends of the contacts 9 may be bent inwardly so as to increase the contact pressure on the terminals. The contacts and the liquid contact circuit closer are then inserted into the housing, and the ends of the contacts 9 are secured to the bosses 10 by the 30 spun-over portions 11 of inserts 12. The circuit closer is now securely held in the housing and is supported for rotation about its axis. Terminal screws 13 are then threaded into the inserts 12. The handle 21 is then placed on the housing so 35 that the flange 22 engages the curved surface 23, and the projection 25 fits within the depression 26 in the terminal 1 adjacent the partition 8. The dust cover 32 placed over the housing and the mounting strap dropped over the handle and secured to the housing by screws 31, thereby holding the dust cover on the top of the housing. When the mounting strap is secured in place, the springs 27 exert a downward force on the handle which holds the handle on the circuit closer and 45 the curved surface 23 and also exerts a downward force on the circuit closer which increases the contact pressure between the contacts 9 and the terminals 1.

In the use of the switch, the switch is mounted 50 in an outlet box so that the right-hand end of the mounting strap 30 is at the top of the box. The terminals 13 are then connected in one side of a two-wire circuit, and the terminals 19 are connected in the other side of a two-wire circuit. The operation of the switch is diagrammatically 55 shown in Fig. 3. From this figure, it is apparent that as the handle 21 is raised, the liquid contact circuit closer will be moved to a position in which the opening 5 in the diaphragm 3 is above the mercury in the circuit closer, and the circuit between the terminals of the liquid contact circuit closer is therefore broken. Since the terminals of the liquid contact circuit closer are connected in one side of a two-wire circuit, the opening of the liquid contact circuit closer interrupts the current which was flowing in the two-wire circuit. Continued raising 65 of the handle 21 causes the rod 33 to engage the lower spring strip 17 and thereby separate the contacts 20, thus opening the other side of the circuit. As the circuit has been broken by the opening of the liquid contact circuit closer, no current is flowing when the contacts 20 are separated. Upon lowering of the handle 21, the 70 rod 33 will first be moved away from the lower

spring strip 17 and the contacts 20 will be closed. Since this closes only one side of the two wire circuit, no current flows upon closing of the contacts 20. Continued downward movement of the handle 21 causes the opening 5 in the diaphragm 2 of the circuit closer to be submerged in the mercury, thereby completing the circuit between the terminals of the circuit closer and closing the other side of the two wire circuit. As soon as the circuit is closed by the circuit closer, current may flow in the two wire circuit. It is therefore apparent that although only a single liquid contact circuit closer is used in this switch, the making and breaking of the two wire circuit is completed through the liquid contact circuit closer.

It is apparent that by different positioning of the hole 5 in the diaphragm and the contacts 17, the circuit controlled by the switch may be closed with the handle in the raised position and also the switch may be mounted in other than vertical positions.

No claim is made in this application to the arrangement of the contact strips 9 in the housing, the supporting of the circuit closer on the projections 15 on the contact strips, or the arrangement for holding the handle 21 on the circuit closer and connecting it thereto, these features being claimed in my applications S. N. 49,928 and 49,930, both filed Nov. 15, 1935.

What I claim as new and desire to secure by Letters Patent of the United States is:

1. In combination, a liquid contact circuit closer having opposed cup-shaped terminals, means for supporting the circuit closer for rotation about the axis of its terminals, a switch including separable contacts, a partition between said switch and said circuit closer having an arcuate surface concentric with the adjacent terminal of the circuit closer, a handle bearing on said arcuate surface and said adjacent terminal, said handle and terminal having interfitting portions for preventing relative rotation therebetween, and an operating connection between said handle and said switch.

2. In combination, a liquid contact circuit closer having opposed cup-shaped terminals, means for supporting the circuit closer for rotation about the axis of its terminals, a switch including a contact carried by a spring strip, a partition between said switch and said circuit closer having an arcuate surface concentric with the adjacent terminal of the circuit closer, a handle bearing on said arcuate surface and said adjacent terminal, said handle and terminal having interfitting portions for preventing relative rotation therebetween, and a projection on said handle engaging said spring strip for operating said switch.

3. In combination, a liquid contact circuit closer having opposed cup-shaped terminals, contacts engaging said terminals, said contacts and said terminals having complementary projections and depressions whereby the circuit closer is supported for rotation about the axis of its terminals, a switch including a contact carried by a spring strip, a partition between said switch and said circuit closer having an arcuate surface concentric with the adjacent terminal of the circuit closer, a handle bearing on said arcuate surface and said adjacent terminal, said handle and terminal having interfitting portions for preventing relative rotation therebetween, and a projection on said handle engaging said spring strip for operating said switch.

4. In combination, a liquid contact circuit closer having opposed cup-shaped terminals, means for supporting the circuit closer for rotation about the axis of its terminals, a switch including separable contacts, a partition between said switch and said circuit closer having an arcuate surface concentric with the adjacent terminal of the circuit closer, a handle bearing on said arcuate surface, said handle having a connection with said circuit closer for rotating the circuit closer, and an operating connection between said handle and said switch.

5. In combination, a liquid contact circuit closer, means for supporting the circuit closer for rotation about an axis, a switch including separable contacts, a partition between said switch and said circuit closer having an arcuate surface concentric with said axis, a handle bearing on said arcuate surface, an operating connection between said handle and said circuit closer, and an operating connection between said handle and said switch. 5
